UNITED STATES PATENT OFFICE.

ALICE HARRIS, OF KANSAS CITY, MISSOURI.

DESIGN FOR A PENDENT MIRROR OR SIMILAR ARTICLE.

SPECIFICATION forming part of Design No. 36,557, dated September 15, 1903.

Application filed June 16, 1903. Serial No. 161,757. Term of patent 3½ years.

To all whom it may concern:

Be it known that I, ALICE HARRIS, a citizen of the United States, residing at Kansas City, in the county of Jackson and State of Missouri, have invented a new, original, and ornamental Design for a Pendent Mirror or Similar Article, of which the following is a specification.

The drawing shows a side elevation of the invention.

What I claim as new, and desire to secure by Letters Patent, is—

The ornamental design for a pendent mirror, or similar article, as shown.

In testimony whereof I affix my signature in the presence of two witnesses.

ALICE HARRIS.
